UNITED STATES PATENT OFFICE

169,389

STOCKING

Isidor Rabinowitz, Philadelphia, Pa.

Application March 20, 1952, Serial No. 18,977

Term of patent 14 years

(Cl. D47—7)

To all whom it may concern:

Be it known that I, Isidor Rabinowitz, a citizen of the United States, residing at Philadelphia, Pennsylvania, have invented a new, original, and ornamental Design for a Stocking, of which the following is a specification, reference being had to the accompanying drawing, forming a part hereof.

Fig. 1 is a rear elevational view of the lower portion of a stocking embodying the design.

Fig. 2 is a perspective view of the same.

I claim:

The ornamental design for a stocking, as shown.

ISIDOR RABINOWITZ.
